UNITED STATES PATENT OFFICE.

CLARENCE W. PETERSON, OF TRACY, CALIFORNIA.

DESIGN FOR A REFRESHMENT STAND.

Application filed February 26, 1929. Serial No. 30,213. Term of patent 7 years.

To all whom it may concern:

Be it known that I, CLARENCE W. PETERSON, a citizen of the United States, residing at Tracy, in the county of San Joaquin, State of California, have invented a new, original, and ornamental Design for Refreshment Stands, of which the following is a specification, reference being had to the accompanying drawing, forming part thereof.

Fig. 1 is a front view of a refreshment stand, showing my new design, and
Fig. 2 is a side elevation of the stand.

I claim:

The ornamental design for a refreshment stand, as shown.

CLARENCE W. PETERSON.
